UNITED STATES PATENT OFFICE.

EZRA S. BUCKNAM, OF PHILADELPHIA, PENNSYLVANIA, ASSIGNOR TO THE J. G. BRILL CO.,
OF PHILADELPHIA, PENNSYLVANIA.

SEMI-CONVERTIBLE CAR.

No. 920,020.

Specification of Letters Patent.

Patented April 27, 1909.

Application filed August 12, 1908. Serial No. 448,085.

To all whom it may concern:

Be it known that I, EZRA S. BUCKNAM, a citizen of the United States, and a resident of the city of Philadelphia, county of Philadelphia, and State of Pennsylvania, have invented a new and useful Improvement in Semi-Convertible Cars, of which the following is a specification.

The object of my invention is to provide a car of the so-called semi-convertible type, particularly suitable for high speed service, and it has more particularly for its object a sash and post construction by means of which an upper sash may be moved independently of a lower sash so that the car window may be opened either at its top or bottom, as desired. This object is accomplished by my invention as detailed below.

For a more particular description of my invention, reference is to be had to the accompanying drawings, forming a part hereof, in which:

Figure 1 is a sectional elevation showing a stanchion and the sash adjacent thereto in their closed position. Figs. 2 and 3 are sectional views taken on the lines 2—2 and 3—3 respectively, of Fig. 4, looking in the direction of the arrows. Fig. 4 is an enlarged view of the structure shown in Fig. 1 near the line 2—2. Fig. 5 is similar to Fig. 4 except that the view is taken near the line 3—3. Fig. 6 is a detailed view showing a portion of the lower sash.

Throughout the various views of the drawings, similar reference characters designate similar parts.

My improved car 1 is provided with the usual stanchions 2 which are connected by the window sill 3 and letter boards 4, and by the roof 5, deck rail 6, head-lining 7, and molding 8, all of which may be of the conventional form except for the differences hereinafter noted. The stanchion 2 also has the usual parting strips 2^a and 2^b, inside and outside respectively. The stanchion (only one is shown) 2 is provided with pintle grooves 9 and 10 respectively. The pintle-groove 9 extends from a point below the letter board 4 in an upwardly and inwardly undulating direction to a point near the roof 5 and over the molding 8. This pintle groove 9 is shaped substantially as shown in Figs. 1

and 2 so as to conform to the structure of the car.

The upper sash 11 is provided on its side frames with suitable pintles 12 located near its upper edge and which slide in the groove 9 thereby determining the movement of the upper end of that sash. The lower edge of the sash is provided with a sliding bolt 13, 60 which is adapted to enter special holes formed in the base of the groove 9 in the conventional manner, so as to support the sash in any of several positions. The upper one of these holes is shown in dotted lines in Fig. 4.

The lower sash 14 overlaps the upper sash 11 in the conventional manner, and is provided with a sliding bolt 15 near its lower edge mounted as usual, near the hand-lift 16, 70 and a bolt actuating handle 17. This sash 14 near its upper edge is provided with a pintle 18 that slides freely in the pintle groove 10. The pintle groove 10 is preferably shaped as shown in Fig. 1, its upper end terminating in the enlargement 19, in which only the lower edge 20 is operative when the sash 14 is raised, its lower end terminating at the sill 3. When the sash is lowered the pintle 18 is shifted from the lower edge 20 to the 80 groove 10, as is obvious. The pintle 18 may be of any suitable construction. Heretofore, the pintles sliding in grooves have been mere pins or projections, sometimes provided with a bushing or sleeve to act as a 85 roller. The pintle 18 preferably consists of a plate 21 from which extends the ear 22 on which a shoe 23 is pivotally mounted. The shoe 23 has a surface adapted to rub against the inner wall of the groove 10 and the edge 90 20 whereby a large wearing surface is utilized so that the wear on the sides of the groove 10 is reduced to a minimum.

The stanchion 2 is preferably recessed at 24 to receive a metal wear-plate (see Fig. 3) 95 against which the shoe 23 rests when the sash 14 is in its lowest position, so that the sash 14 is forced positively and firmly against the upper sash 11 whereby a close joint is maintained. Below the wear-plate 25 the groove 10 is extended downwardly and outwardly so as to be in the plane of the sash 14. The base of the groove 10 is provided with any number of suitably located holes for the bolt

15. These are located as may be convenient, one being placed at 26 as shown in Fig. 4 to receive the bolt 15 when the sash is in its most elevated position, and another at 27 for 5 an intermediate position.

In the construction above described each sash may be raised and stored under the roof; and lowered independently of the other sash, thereby securing great flexibility of 10 disposition of the sash for ventilation.

It is obvious that the upper sash 11 cannot be opened from the inside of the car without raising the lower sash 14 so that the bolt 13 can be reached.

15. While I have shown and described one embodiment of my invention, it is obvious that it is not restricted thereto but is broad enough to cover all structures that come within the scope of the annexed claims.

20. What I claim is:

1. In a car, a plurality of sashes, stanchions having independent pintle-grooves, and sashes with pintles entering said grooves, so that one sash may be raised or lowered independently of the other, one of said pintles being provided with a pivotally mounted shoe.

2. In a car, stanchions, upper and lower sashes, pintles near the upper edge of said 25 upper sash adapted to move in one of said pintle ways, and pintles and bolts on the

lower sash adapted to move in the other of said pintle ways, the pintles of the lower sash being provided with pivotally mounted shoes.

35

3. In a car, stanchions, upper and lower sashes adapted to slide between said stanchions, pintle ways in said stanchions, pintles on said sashes, one of said pintles being provided with a plate, an ear, and a shoe pivoted to said ear.

40

4. In a car, stanchions having independent pintle grooves above the letter-board one of which extends in an upwardly and inwardly undulating direction, and sashes with 45 pintles entering said grooves and movable entirely independently of each other.

45

5. In a car, stanchions having independent pintle grooves above the letter-board one of which extends in an upwardly and inwardly undulating direction, sashes with 50 pintles entering said grooves and movable entirely independently of each other, the pintles of the lower sash being provided with pivotally mounted shoes.

55

Signed at the city of Philadelphia, county of Philadelphia, and State of Pennsylvania, this 10th day of August, 1908.

EZRA S. BUCKNAM.
